Inventor

UNITED STATES PATENT OFFICE.

SAMUEL W. RUSHMORE, OF PLAINFIELD, NEW JERSEY.

RADIATOR FOR COOLING FLUIDS.

Application filed September 13, 1921. Serial No. 500,381.

To all whom it may concern:

Be it known that I, SAMUEL W. RUSHMORE, a citizen of the United States, and resident of Plainfield, in the county of Union 5 and State of New Jersey, have invented certain new and useful Improvements in Radiators for Cooling Fluids, of which the following is a specification.

My present invention is shown as embodied in an air cooled radiator suitable for use in connection with the internal combustion engines used on automobiles, trucks, flying machines, etc.; and certain features of the invention are especially useful when 10 the radiator is used as an upflow steam condenser operating in accordance with the method described in my Patent 1,378,724, granted May 17th, 1921; but it will be evident that various features of the invention 15 may be employed for other purposes and in other relations.

The illustrative embodiment disclosed herein is a radiator of the type in which the "honeycomb" or heat radiating element 20 of the structure is built up of horizontal tubes formed and assembled in short parallel lengths with the tubular interiors serving as front-to-rear draft passages for the cooling air, while the interspaces between the tubes afford a multiplicity of parallel paths for up or down flow of the fluid 25 which is to be cooled. The tubes may be square or hexagonal or round in cross section, preferably bearing upon each other 30 at the end portions only, said portions being enlarged so as to properly space apart the intermediate or body portions of adjacent tubes. The enlarged ends of the tubes are preferably hexagonal so that they naturally 35 fit together solidly when assembled in properly staggered rows. While a hexagonal shape is more desirable as requiring less deformation and expansion of the ends of the tubes, nevertheless, so far as concerns 40 the main functional features of my invention the ends might be squares or equilateral triangles.

In the case of radiators designed for water cooling, the hexagonal ends must be enlarged to a very considerably greater diameter than the body portion in order to afford considerable interspaces for the required low resistance flow of water therethrough; and the required enlargement must be maintained for all tubes throughout the radiator from top to bottom. Such enlargement

frequently results in splitting of the metal during the expanding operation, and the losses from this cause are considerable.

When operating as an up-flow steam condenser, however, the volume of up-going steam and returning condensate is greatest at the bottom and becomes less and less the higher up it extends in the radiator. I, therefore, construct my radiator of tubes 60 all having the same size for the enlarged ends, square or hexagonal, as the case may be, but the body portions between the enlarged ends are of progressively larger diameter, giving progressively smaller interspaces toward the top of the radiator. Thus at the bottom of the radiator the air flow section is small and the steam and water section is considerable, while at the top, the air flow section is greater and the steam and 70 water section is smaller.

As a result of this construction, the upper part of my radiator shows an increase in the developed air cooled surface of 15% to 20% over that available where the tubes 80 are all of the relatively small cross section as required when water is used as a cooling medium. This makes it possible to embody a greater air cooled surface area in a given front area, with a proportional reduction in front resistance to passage 85 through the air at high speed. This is of great importance on all high speed vehicles particularly air-planes.

Furthermore, by reducing the amount to 90 which the ends of the tubes have to be expanded, I effect a considerable reduction in cost of manufacture and practically eliminate waste due to splitting of the ends in the expanding dies, which is now a serious 95 item of expense in the cost of manufacture of water cooling radiators of this type. Where the steam is boiled off from the water in close proximity with the lowermost row of the tubes, as in practice of my patented 100 method, the splashing of the water may make it desirable to have the interspaces for the lowermost rows of tubes almost as large as those now used for water cooling. From the bottom up, however, the required interspaces permit using larger tubes with only slightly expanded ends. It would be desirable to make the tubes progressively larger for each succeeding higher row, but in most cases it will be found that sufficiently 110 good results can be achieved and the cost of manufacture very desirably decreased,

by using one size for several rows, so that only a limited number of sizes is required.

The above and other features of my invention may be more fully understood from the following description in connection with the accompanying drawings, in which:—

Fig. 1 is a front elevation showing the relations of the air passages in one type of radiator constructed in accordance with my present invention;

Fig. 2 is a detail end view showing the internal side supports for the tubes in structure shown in Fig. 1; and Fig. 2^a is a side elevation of the assembled tubes shown in Fig. 2.

It will be understood that Fig. 1 is on a reduced scale; that the scale for Figs. 3, 4, and 5 is somewhat larger; and that the scale of Figs. 2 and 2^a is still larger.

Figs. 3, 4, and 5 are sectional detail views showing the proportions and relations of three adjacent tubes in three different groups on the levels of dotted lines 3—3, 4—4, and 5—5, respectively, of Fig. 1;

Fig. 6, 7, and 8 are practically full size end views of the three sizes of tubes employed.

In these drawings the tubes constituting the honeycomb are shown as having body portions 1 which are expanded at the ends to form hexagonal enlargements 2. The tubes are all of the same length, and may be, say $2\frac{1}{2}$ or 3 inches, and the hexagonal enlargements are all of the same diameter, and may be, say $\frac{3}{8}$ inch. The body portions 1, however, are shown as of three different sizes, varying from, say $\frac{1}{16}$ inch for the size shown in Figs. 3 and 6, to say $\frac{1}{8}$ inch for the size shown in Figs. 5 and 8.

While actual sizes may vary quite widely, it will be evident from the above that the minimum cross section for flow of air through the tubes may be two or three times as great for the upper tubes as for the lower tubes, while the minimum interspaces 3, as indicated in Figs. 3, 4 and 5, may be one-half to one-quarter as great for the upper tubes as for the lower tubes. As shown in the drawings, the tubes having small body diameter and large interspaces, comprise the lower six rows, the next larger size the intermediate six rows, and the largest size the top six rows. Obviously, however, the dimensions, the number of sizes employed, the number of rows of each size, number of tubes in each row and the total number of rows, may be varied within wide limits.

The honeycomb may be built up by assembling the tubes in any suitable support, and soldering or brazing the enlarged ends by dipping in molten tin or solder.

The body portion or shell of the radiator comprises the peripheral wall 4 and front and rear walls 5 and 6. The thickness of the radiator is approximately the same as

the length of the tubes but the height of the radiator is such as to leave a space 7 at the bottom and a space 8 at the top.

In operation the steam in space 7 rises in the interspaces 3 to the height required for condensing it. The condensed water returns by gravity into the space 8 from which it may be withdrawn in any desired way.

For practice of the invention described in my above-mentioned patent, the flow of 75 boiling hot water and steam from the water jacket of the engine is short-circuited through the space 7, which then operates as a steam separating chamber, but it will be obvious that either hot water or steam from 80 any desired source, either separately or together, may be discharged in space 7. An inlet for the space 7 is conventionally indicated at 9 and an outlet at 10.

The above described principles of progressively narrowing the interspaces for decreasing the flow capacity of the interior paths for the fluid to be cooled, as also progressively enlarging the sizes of the air passages to increase the cooling surface, may 85 be practiced either separately or in combination, for other than up-and-down variations of flow capacity and cooling rates. As for instance where a centrally located fan throws a more powerful cooling draft 95 on the central area of the honeycomb than elsewhere or where the sides of the honeycomb are of less height than at the center, larger tubes may be used, or the tubes may be more closely set, for the more ineffective 100 portions of the honeycomb area.

I claim:

1. An up-flow condenser comprising an air cooled radiator of the automobile type having upper and lower chambers; means 105 for discharging boiling water or steam into said lower chamber and withdrawing water therefrom; and an intermediate "core" or "honeycomb" embodying a multiplicity of transverse passages for flow of the cooling air, the walls defining said passages being spaced apart to afford interspaces for flow of fluid medium to be cooled therein, said air passages at different levels being of progressively larger flow section from bottom 110 to top of the radiator and the interstices for up-flow of steam being of progressively less flow section from bottom to top of the radiator.

2. An up-flow condenser comprising an 120 air cooled radiator having a multiplicity of transverse passages for flow of the cooling air, the walls defining said passages being spaced apart to afford interspaces for flow of fluid medium to be cooled therein, said interspaces being of progressively less flow-section toward the top of the radiator, the air passages being arranged in successive horizontal rows, with the horizontal distances between the axes of adjacent pas- 125 130

sages in the same row substantially the same for all rows regardless of the diameters of the tubes comprising the rows.

3. An up-flow condenser comprising an air cooled radiator having a lower chamber; means for discharging boiling water or steam into said lower chamber and for withdrawing water therefrom comprising short horizontal tubes having enlarged hexagonal ends assembled in parallel relation with the said hexagonal ends interfitting, the hexagonal ends being all of substantially the same diameter and the

intermediate body portions of the tubes being of smaller diameter for the lowermost 15 tubes than for those higher up.

4. A radiator as specified in claim 3 with the further feature that the diameters of the tubes are progressively greater from the bottom of the radiator toward the top 20 thereof.

Signed at Plainfield, in the county of Union and State of New Jersey, this 10th day of September, A. D. 1921.

SAMUEL W. RUSHMORE.
